MOBILE FOOD SALES UNIT

Al Lapin, Jr., Los Angeles, Calif., assignor to International
Industries, Inc., North Hollywood, Calif., a corporation

Filed Nov. 4, 1964, Ser. No. 82,458

Term of patent 14 years

(Cl. D14—3)

FIGURE 1 is a perspective view of a mobile food sales unit showing my new design;

FIGURE 2 is a rear elevational view;

FIGURE 3 is an elevational view of the side not shown in FIGURE 1;

FIGURE 4 is a front elevational view; and

FIGURE 5 is a rear perspective view from the right side, to a reduced scale, with the side and back open to show the interior.

The dominant features of my design reside in the portions shown in full lines.

I claim:

The ornamental design for a mobile food sales unit, substantially as shown and described.
